UNITED STATES PATENT OFFICE.

HERBERT E. IVES, OF MONTCLAIR, NEW JERSEY, ASSIGNOR TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed May 8, 1924. Serial No. 711,755.

This invention relates to the transmission of pictures by electricity and more particularly to a novel combination of electromagnetic and optical devices suitable for reproducing a pleasing picture.

Many attempts have been made to transmit pictures by electricity and many varieties of equipment have been disclosed. Problems of various kinds have arisen. In 10 many instances the equipment employed was not suitable for use over long distances. In other cases the speed of transmission was too slow. In still other cases the apparatus was so complicated as to be impracticable. In still other instances specially constructed transmission lines were required.

An object of the present invention is to obviate these difficulties and to accomplish 20 the transmission of pictures by electricity in a thoroughly practicable manner.

In one embodiment of this invention, the characteristics of the picture are transmitted as modulations of a voice frequency carrier wave, which can therefore be transmitted over ordinary telephone lines or circuits. Such modulated wave is impressed directly upon a single string light valve, the natural frequency of vibration of the string 30 being substantially the same as that of the carrier wave. By means of a simple optical arrangement controlled by the light valve, the picture is reproduced in the form of a plurality of parallel lines of uniform density 35 and varying width. This reproduction is peculiarly suitable for making a half tone zinc or copper plate.

The novel features which are considered characteristic of this invention are set forth 40 with particularity in the appended claims. The invention both as to its organization and method of operation, together with other objects and advantages thereof, will be explained in the following description, 45 having reference to the accompanying drawing consisting of the following figures:

Fig. 1 is a circuit diagram of a sending terminal arrangement for producing a carrier wave modulated in accordance with the 50 characteristics of the picture to be transmitted.

Fig. 2 is a circuit diagram of a receiving

terminal arrangement for reproducing the picture.

Fig. 3 is a diagrammatic showing of the 55 optical system of Fig. 2 (partly in cross section) as viewed from above.

Fig. 4 is a side view of the light valve assembly.

Figs. 5, 6 and 7 show details of the light 60 valve.

Fig. 8 is a showing of a section of the reproduced picture greatly enlarged.

Figs. 9, 10 and 11 are curves showing how the exposure of the reproduced picture is effected under different conditions.

Fig. 12 is a fragmentary showing of the aperture forming members of the light valve for reference in connection with the explanation of Figs. 9, 10 and 11.

The same reference characters are used in the several figures to indicate the same elements.

Referring now to Fig. 1 a modulator M is supplied with carrier waves from a source 75 C and with picture current from a photoelectric cell P and picture amplifier PA. Modulated carrier waves from the modulator M are impressed upon the transmission line L through a filter SPF. The 80 photoelectric cell P is located within a transparent drum 5 which is driven in any suitable manner by shaft 6. Mounted on the drum 5 is a transparency 7 of the picture to be transmitted. Light from a source 85 8 is focussed by means of lens 9 upon the transparency of the picture through an aperture in screen 10. The amount of light affecting the photoelectric cell P is determined by the tone value or density of the 90 elemental area of the transparency 7 which is at that instant adjacent to the aperture in the screen 10 at the focal point of the light beam. The amount of light within the photoelectric cell P in turn determines the 95 amount of current which can flow from the battery 11 through the photoelectric cell P and resistance 12 and consequently, the potential drop across the resistance 12, which 100 potential is impressed upon the input circuit of the picture amplifier PA. The amplified picture current is impressed upon the modulator M by resistance 13 simultaneously with carrier current from the source

C. Modulated carrier waves from the modulator M are then impressed upon the line L in the manner previously noted.

Referring now to the receiving terminal arrangement of Fig. 2, modulated carrier waves from the line L after passing through the filter RP¹ are amplified by amplifier

RA, and impressed by means of transformer 15 on the string 16 of light valve V. The string 16 is suspended in a magnetic field and is arranged to vibrate in a direction transverse to the plane of the paper.

Light from the source 18 is directed by means of lens 19 upon the conductor 16.

15. The source 18 is preferably an incandescent lamp with spiral filament arranged coaxially with the lens 19 so that the aperture forming elements of the valve V are intensely and uniformly illuminated. The string 16 is one of these aperture forming elements; the screen 23, another; and the jaws 30 and 31, the others. The relative location of these members for the "no-exposure" condition is shown in Fig. 12.

25. Referring to Fig. 3 for further details of the optical system, a winding 17 is mounted on a hollow central core of a magnetic frame 32. A magnetic plate 33 connected to the frame 32 provides an air gap in which is located the string 16 and the other aperture forming members 30, 31 and 23. The string 16 is arranged to vibrate crosswise with respect to the aperture between members 30 and 31.

35. Referring now to Figs. 4 to 7 inclusive, which illustrate the construction of the light valve, the plate 33 is connected to the frame 32 by means of knurled nuts 34, 34. The string 16 is suspended between the terminal 40 and the post 36 and held at its lower end by the terminal 37. The aperture forming members 30 and 31 are mounted on flexible studs so that the opening between them may be adjusted by means of screws 38 and 39. For purposes of simplicity this aperture will hereinafter be called the horizontal aperture, while the aperture in member 23 will be called the vertical aperture. The vertical aperture is also adjustable, the adjustment being effected by substituting different screens having different sizes of apertures.

45. It is seen from Fig. 3 that the light from source 18 passes through the hollow core of magnetic frame 32. If the string 16 is displaced with respect to the horizontal aperture between members 30 and 31 light will pass through the lens 20 to expose the light sensitive record blank 21 mounted on drum 22 which is rotated by means of shaft 24. The lens 20 is so arranged as to cause an image of the light valve aperture to be formed upon the record blank 21.

55. The light sensitive surface of the record-65 ing blank is such that it is exposed to full

depth by a single exposure to light from source 18. Additional exposures of the same area have no effect to change its tone value. Thus the developed record possesses only two tone values, one corresponding to exposure and the other corresponding to no exposure.

60. The adjustability of the horizontal aperture formed by jaws 30 and 31 permits of selecting any portion of the incoming current amplitude range to cause the exposure of the record blank. For example, if the horizontal aperture is just equal to the width b of the string 16, exposure results as soon as the string 16 begins to move. If the horizontal aperture is less than the width b , appreciable movement is required before exposure begins. In other words a finite value of current must be impressed upon the string 16 to cause exposure.

65. The transmission of pictures the arrangement of Fig. 1 is combined with that of Fig. 2 by connecting lines L together by means of a telephone line or circuit. The telephone circuit may be a carrier channel 70

or a radio telephone channel. The drums 5 and 22 are driven in synchronism by any suitable arrangement such, for example, as that shown in the copending application of

M. B. Long Serial No. 681,347, filed December 18, 1923. They are not only rotated in synchronism, but are also moved axially relatively to the shafts 6 and 24. As the drum 5 rotates carrier current modulated in accordance with the varying tone values of the

successive elemental areas of the picture is transmitted over line L and impressed in amplified form upon the string 16 of light valve V. The movement of string 16 relative to the horizontal aperture between 100

members 30 and 31 allows more or less light from the source 18, depending upon the amplitude values of the envelope of the modulated waves, to affect the elemental areas of the light sensitive record blank 21 on the

drum 22. The light sensitive record blank 21 is accordingly exposed for the reproduction of the picture in a manner now to be described in connection with Figs. 8 to 12 inclusive.

115. Fig. 8 shows a portion of the developed picture greatly enlarged. The width of surface exposed during each revolution of the reproducing drum 22 or the width of the trace is represented by the distance b . This width is determined by the horizontal aperture or the distance between the jaws 30 and 31. Preferably this width b is equal to the axial travel of the drum per revolution.

120. The cross hatched area represents the surface which has been exposed to light from the source 18 due to the vibration of the string 16. Actually this surface is of uniform density. The shape of the boundary line between the exposed and unexposed sur-

faces, will be explained hereinafter in connection with Figs. 9, 10 and 11.

From Fig. 8 it is clear that the complete picture is composed of a plurality of parallel lines of varying width, each line consisting of the adjacent exposed parts of two successive traces. These lines may merge to give a continuously exposed area, such as that between lines x and y . In the preferred form, however, a maximum exposure results in distinct lines, which form is particularly valuable for use in the preparation of zinc or copper half-tone plates. For this preferred form, the adjustment of the system is such that the string 16 of the light valve V never uncovers quite half of the space between the jaws 30 and 31.

In Figs. 9, 10 and 11 the method of exposing one half of a trace under various valve and aperture adjustments and with different transmitting speeds is illustrated. The distance a represents the space along the trace which is exposed at any given instant and is determined by the vertical aperture in member 23. The distance c represents the distance traveled by a given point on the record blank during one cycle of the carrier wave and hence during one complete vibration of the string 16 of the light valve V. The arrows show the direction of motion of the record blank relatively to the aperture forming members of the light valve.

From the foregoing explanation and by reference to Fig. 12, it is clear that the solid curve 50 represents the trace on the record blank of the movement of the point m on the edge of the string 16 as the string vibrates. Likewise, the dotted curve 51 represents the trace of the movement of point n which is a point on the same edge of the string 16, but on the opposite edge of the vertical aperture in member 23. Each of the other points located between points m and n will trace similar curves. As the string 16 moves downward in Fig. 12 an area of the record blank will be exposed, one part of which will be defined by the edge of jaw 31 and the rest by the moving edge of the string 16 between the points m and n and the edges of the aperture in screen 23. The right sloped cross hatched area 52 is exposed during one vibration; the left sloped cross hatched area 53, during the next vibration and the vertical cross hatched area 54, during the third vibration. Succeeding vibrations are shown in the same manner and may easily be traced.

For the purpose of simplicity, the exposure due to the movement of the edge of the string 16 opposite the edge $m-n$ has not been shown in Figs. 9, 10 and 11. The portions of the curves 50 and 51 above the center line are not actually exposed on the record blank because of the screening effect of

the jaw 31. They are shown merely for purpose of explanation.

In each of Figs. 9, 10 and 11 the frequency of the carrier waves are the same. In Fig. 9, two and one half cycles of the carrier wave occur while the record blank moves through the distance a . This distance determines the resolution of the picture in the direction of movement of the record blank; the resolution in the direction at right angles to this is determined by the distance b . The effect of a single small amplitude vibration, if it occurs between two highly amplified vibrations, may thus be entirely lost. This is illustrated by the right-hand portion of Fig. 9, where the exposure due to the wave peak 55 is entirely masked by the exposures due to the wave peaks 56 and 57.

In Fig. 10 the speed of movement of the record blank is the same as in Fig. 9, but the exposure a is only two-fifths as large. In this arrangement each wave peak performs its function and maximum resolution of the picture with continuity of line results.

In Fig. 11 the speed of movement of the record blank is double that of Figs. 9 and 10. Accordingly, only one-half cycle of the carrier wave occurs while the record blank moves through the distance a , the result is that the exposed area becomes a wavy line. If the speed is still further increased, the exposed area appears as discreet areas.

As an example of the actual values employed in an arrangement giving a record somewhat like that of Fig. 9, the following values are given:

Size of picture, 5 x 7 inches; time of reproduction, 4 minutes; axial travel of drum, 7 inches; axial travel of drum for each revolution, .02 inches; total revolutions for the picture, 350; circumference of drum 22, 6 inches; linear travel of recording drum, 2100 inches; linear speed of recording drum, 525" per minute or 8.75" per second; frequency of carrier wave, 1300 cycles per second; distance c (linear travel per cycle), .00673 inches; distance a (exposure in direction of motion), .02 inches; cycles of carrier wave for exposure a , 2.1.

The actual dimensions of the light valve elements (see Fig. 12) are $a=.01"$ $b=.01"$. The exposure on the record blank with the valve wide open is a square $1/50 \times 1/50$ of an inch.

In a modification of this arrangement the dimension a (see Fig. 12) is made one half the dimension b , thus $a=.005"$ and $b=.01"$. The exposure on the record blank with the valve wide open will be $1/130$ of an inch in the direction of movement and $1/65$ of an inch axially. The sizes of these exposures are obtained by means of the optical system including the lens 20.

The damping of the string 16 should be

such that the instantaneous amplitudes of vibration will be substantially proportional to the amplitudes of the envelope of the modulated carrier wave. A criterion for the amount of damping is given in a co-pending application of E. C. Wente, Serial No. 701,016, filed March 22, 1924.

From the foregoing description it will be seen that a simple, effective and practicable picture transmission system has been provided. The characteristics of the picture are transmitted as modulations of a voice frequency carrier wave and can therefore be transmitted over any line or circuit which is suitable for the transmission of telephone conversation. The reproducing equipment is comparatively simple and the reproduced picture is not only pleasing in appearance, but is in a form suitable for the reproduction of half tone prints with a minimum of photographic manipulation.

While one embodiment of the invention has been specifically described, the scope of the invention is to be limited only by the appended claims.

What is claimed is:

1. The method of reproducing a picture which comprises producing a carrier wave modulated in accordance with the characteristics of the picture, exposing opposite edges of linearly aligned areas of a light sensitive surface to a degree proportional to the amplitude of said modulated carrier wave, and successively exposing adjacent groups of linearly aligned areas to complete the picture.
2. In a system for the transmission of pictures by electricity, means to modulate a carrier wave in accordance with the elemental tone values of the picture, means to impress such modulated carrier wave upon a single string light valve, said string normally completely covering an aperture in said valve and vibrating to uncover the aperture on either side by an amount directly proportional to the amplitude of said modulated carrier wave and an optical system controlled by said light valve for reproducing the picture.
3. In a system for the transmission of pictures by electricity, a carrier wave modulated in accordance with the elemental tone values of the picture, a moving light sensitive record blank, a source of light for exposing said record blank, a screen having an aperture located in the path of the light from said source, a single movable string adapted when quiescent to prevent exposure of the record blank by light from said aperture,

and means to vibrate said movable string in accordance with said modulated carrier wave to expose said record blank by uncovering said aperture on either side by an amount directly proportional to the amplitude of said modulated carrier wave.

4. A light valve comprising a magnetic frame, a magnetic plate connectable to said frame and forming an air gap therewith, and aperture forming members mounted on said plate.

5. A light valve comprising a magnetic frame, a central hollow magnetic core for said frame, a magnetizing coil surrounding said core, a magnetic plate connectable with said magnetic frame and forming a concentrated air gap with said hollow core, terminal supports mounted on said plate and a conducting member connected between said supports and adapted to vibrate in said air gap.

6. A light valve comprising a magnetic frame, a central hollow magnetic core for said frame, a magnetizing coil surrounding said core, a magnetic plate connectable with said magnetic frame and forming a concentrated air gap with said hollow core, terminal supports mounted on said plate, a conducting member connected between said supports and adapted to vibrate in said air gap, a screen having an aperture normally registering with said conducting member, and means to adjust the width of said aperture.

7. A light valve comprising a magnetic frame, a central hollow magnetic core for said frame, a magnetizing coil surrounding said core, a magnetic plate connectable with said magnetic frame and forming a concentrated air gap with said hollow core, terminal supports mounted on said plate, a conducting member connected between said supports and adapted to vibrate in said air gap, a screen having an aperture normally registering with said conducting member, means to adjust the width of said aperture, and a second screen having an aperture variable in the direction of the length of the vibrating conducting member.

8. A light valve comprising a magnetic circuit including an air gap, a conductor located in said air gap and arranged to move when current flows therethrough, and an adjustable member forming with said conductor a variable aperture for a given value of current.

In witness whereof, I hereunto subscribe my name this 7 day of May, A. D. 1924.

HERBERT E. IVES.
